HEARTH VENT AND ASH DUMP COMBINATION

Albert P. Robinson, Seattle, Wash.

Application January 24, 1955, Serial No. 483,747

3 Claims. (Cl. 126—143)

This invention relates to improvements in fireplace construction, and it pertains more particularly to the details of construction and mode of use of a fireplace hearth air vent.

It is the principal object of this invention to provide an open fireplace, equipped with a hearth vent, located in position at which it will be directly below the burning fuel as contained in the fireplace, thus to furnish air from outside the room as an aid to combustion for better burning and heating efficiency.

It is a further object of this invention to provide a hearth vent of the character above stated, through which ashes from the fireplace may be dumped into an ash pit below the hearth, and through which air may be admitted under control of a door that it pivoted for easy adjustment between open and closed positions and which door is overlaid by a grate whereby the burning fuel will normally be retained against dropping through the vent or air passage to the ash pit.

It is a further object of the invention to provide, as a combination, an air vent door and grate, each adjustably mounted in a frame that is designed to be set down within the fireplace hearth, flush with its top surface; said frame defining an air venting and ash dumping passage into the ash pit, and to provide the ash pit with an outside air inlet through which fresh air may be admitted for supplying the fireplace through the hearth vent whenever such is desired.

Still further objects of the present invention reside in the details of construction of the frame, or housing, which defines the air passage and in which the grate and air vent door are mounted, and in the details of the grate and vent door and in their relationship to each other as applied to the frame.

In accomplishing the above mentioned and other objects of the invention, I have provided the improved details of construction, the preferred forms of which are illustrated in the accompanying drawings, wherein:

Fig. 1 is a vertical section through a residential fireplace of typical construction, showing it as equipped with a hearth vent embodying the improvements of the present invention therein.

Fig. 2 is an enlarged, cross-sectional view through the hearth vent frame, door and grate, and showing the vent door closed and the grate in its normal position of use; the section being taken substantially on the line 2—2 in Fig. 1.

Fig. 3 is a top, or plan view of the frame, with grate and air vent door applied thereto, and each in closed position.

Fig. 4 is a cross-section taken on the line 4—4 in Fig. 3, showing the air vent door in its open position and the grate as raised for the disposal of ashes through the open vent to the ash pit below.

Fig. 5 is a perspective view of the present frame, grate and vent door as assembled in use, showing the vent door closed and the grate lifted to its open position.

2

Fig. 6 is an enlarged detail showing a grate pivot or trunnion as contained in its seat.

Referring more in detail to the drawings:

In Fig. 1 I have illustrated a typical fireplace construction in which 10 designates the back wall of the fireplace combustion chamber, 11 the combustion chamber, 12 the throat passage that opens from the chamber into the chimney flue 13, and 14 the hearth or floor of the fireplace. Beneath the hearth 14 is an ash pit 15; this being closed as required to retain the ashes, and equipped near the top with an inlet 16 through which outside air may be admitted to the pit for flow therefrom to the combustion chamber 11 through the hearth vent of this invention presently to be described.

Set within the hearth, or floor 14, is a rectangular, metal housing, designated in its entirety by numeral 20, whereby a passage between the fireplace chamber 11 and the pit 15 is defined; this housing preferably being located in the hearth near the back wall 10 of the chamber 11, and midway between opposite sidewalls thereof. This frame comprises the opposite sidewalls 21 and 21', as best shown in Fig. 2, and opposite end walls 22 and 22', as seen in Fig. 4. These four walls are joined in a one-piece casting, and are in downwardly converging relationship to provide a housing of hopper form. It is to be observed by reference to Fig. 2 that the sidewalls 21—21' are thickened along their top edges and these parts are formed with vertical inside surfaces 21x. At their lower edges, the sidewalls are likewise formed with vertical inside surfaces as at 21y.

It is shown in Fig. 4 that the end walls 22 and 22' of the frame are also thickened along their top edges, and these parts are formed with vertical inside surfaces 22x, and that the back wall 22 terminates in an inturned, horizontal flange 22f that is located somewhat above the level of the lower edge of the opposite wall 22'. Integrally cast with the end walls 22—22' and in laterally spaced relationship thereon, are vertical flanges 25, as seen in Fig. 5, which are adapted to be embedded in the masonry of the hearth to better retain the housing in position, and also to serve as means for limiting the extent to which frames of this kind can be nested when stacked and nested for storage or shipments.

The opposite vertical surfaces 21x and 22x which bound the upper end of the passage as defined by the frame, provide a rectangular enclosure within which a grate 30 is located. This grate is a single metal plate, formed with a series of parallel slots 31 opening therethrough. Extending from opposite side edges of the grate, near its rear edge, are trunnions 32—32. These are axially aligned and are pivotally contained in seats 33—33 formed in the opposite sidewalls of the frame. The forward edge of this grate is adapted to be swung upwardly about the trunnions from the horizontal position of Fig. 1, to the substantially upright position of Fig. 4. The trunnions, as seen in Fig. 6, are formed with projections, as at 35 which will engage with vertical surfaces of the sockets which form the seats 33 to limit the rearward swing of the grate at a position slightly over dead center. When the grate is in its lowered, or closed position of Fig. 1, it is flush with the hearth surface, and it rests at its forward corners on lugs 38 that are cast in the forward corner portions of the frame, as shown in Figs. 3 and 4.

The lower end of the passage as formed by the four downwardly converging walls of the frame, is equipped with a closure plate or damper 40. This is designed to be supported in a horizontal position as shown in Figs. 1 and 2 to close the passage against a free inflow of air from the pit 15 to the combustion chamber. For this support it is equipped at opposite side edges with axially aligned supporting trunnions 41—41, that are pivotally contained

in seats 42—42 provided therefor in the lower portions of the sidewalls of the frame, as observed in Fig. 2. The trunnions 41 are located substantially closer to the forward edge of the plate than to the back edge, and the plate is formed across its forward edge with a heavy flange or head 43, as shown in Fig. 4 which will, by reason of its weight, hold the plate in horizontal position once it is moved to that position. However, if it is desired to admit outside air to the fireplace through the hearth vent, the plate 40 is swung about its supporting trunnions to the vertical position in which it is shown in Fig. 4, and it will then remain in this position under the weight of a flange 46 that is formed on and extends at right angles to the plate from its topside, at the line of the trunnions.

This flange 46, as will be understood by reference to the showing in Figs. 1 and 2, is adapted to be engaged by the end of a fireplace poker, such as designated at P, to swing the plate 40 from closed to open position, or vice versa. The trunnions of the plate 40 may be formed with projections to engage the sidewalls of their containing seats, like the showing in Fig. 6, thus to establish the closing and opening limits of the plate or damper. In order that the damper plate 40 may not be accidentally displaced from position by reason of its adjustment between open and closed position a crossbar 40 is integrally cast with the frame, transversely of the passage as shown in Figs. 4 and 5 and just rearwardly of the seats as provided for the trunnions 41. When the plate swings upward to closed position, it engages against this crossbar as in Fig. 1.

It will be understood that with the hearth vent applied to the fireplace structure as seen in Fig. 1, outside air can enter the ash pit through the opening 16. Then, if the damper plate 40 is moved to the open position, as seen in Fig. 4, fresh air can pass from the pit, upwardly through the vent and grate, to the fireplace as an aid to fuel combustion. If the door 40 is closed, as in Fig. 1, this free inflow of air is stopped.

Should it be desired to clear the fireplace of ashes, the door 40 and grate are both opened, as shown in Fig. 4, and the ashes may be moved through the hearth vent to the pit.

The advantages of having such a hearth vent for supplying air to the fire are well established and not questioned. It is economical, as it affords means for the producing much heat from a minimum of fuel because of insuring its complete combustion. It compensates for the absence in present day residence construction of means for the admittance of sufficient air to the rooms for proper outflow of smoke and fumes from the fireplace without necessitating the opening of a door or window. It eliminates fireplace smoking and out-puffing of smoke due to down-draft, and it makes possible, the burning of fuel that otherwise would be difficult to burn in a fireplace under normal conditions.

While I have herein shown the grate 30 and door 40 as being mounted in the same frame structure, it is anticipated that they may be mounted in different frames or even be mounted independently of each other in the masonry to provide the same combination. It is the specific combination of grate and ash dump door as used below the grate, in which invention is believed to reside and therefore it is not desired to confine the claims only to a combination that includes a frame structure that is common to both grate and door.

The combination of these parts in an air vent as shown provides for admittance of air to a fire at a point that is

most advantageous and eliminates the difficulties and disadvantages of maintaining a fire in a fireplace that opens into a closed room.

When the fireplace is not in use, the ash dump door 40 can be closed to prevent up-draft drawing air up through the grate and blowing ashes into the room.

Having thus described my invention, what I claim as new therein and desire to secure by Letters Patent is:

1. A hearth vent and ash dump combination comprising a frame structure adapted to be set within the hearth of a fireplace combustion chamber to define a vertically directed passage for the dumping of fireplace ashes to a pit below the hearth, and for an inflow of air to the fireplace chamber from the pit, a grate supported by the frame across the upper end of the passage, for adjustment from a position flush with the hearth surface to a raised position, for the disposal of ashes through the passage, and a door disposed within the lower end of the passage for closing it against an inflow of air, and having supporting trunnions on which it can be swung, independently of the grate from its closed position to an open position for an inflow of air through the passage and grate; said door being weighted at one edge to cause it to be yieldingly retained in closed position when moved to that position, and to be yieldingly retained in its open position when adjusted to that position.

2. A hearth vent and ash dump combination comprising a rectangular frame structure designed to be set down within the hearth portion of a fireplace combustion chamber to define a passage therethrough for the disposal of fireplace ashes to an ash pit below the hearth, and for an inflow of air into the fireplace chamber; said frame having its walls downwardly converging to provide a passage of hopper form; said frame being provided in the top edges of its opposite side portions with aligned upwardly opening trunnion seats, and in said side portions, near the lower end of the passage with aligned trunnion seats, a grate disposed in the upper end of said passage having supporting trunnions projecting therefrom and disposed in the first mentioned trunnion seats to support the grate for swinging between closed and open positions, a door disposed in the lower end of the passage and having trunnions projecting from its opposite sides disposed in the second mentioned trunnion seats to support the door for swinging between a horizontal, passage closing position to a vertical, open position; said door being weighted at one edge in a manner to retain it at either of the positions to which it may be adjusted, and there being a flange extended from the door that is accessible through the closed grate for the manual adjustment of the door from one position to another.

3. A combination as recited in claim 2 wherein the trunnions of door and grate have projections at one side engageable with side surfaces of the seats to limit the opening movements of the door and grate.
